CHARLES A. SMITH, OF NEW YORK, N. Y.

Letters Patent No. 81,424, dated August 25, 1868.

IMPROVEMENT IN LIFTING-JACK.

The Schedule referred to in these Letters Patent and making part of the same.

TO ALL WHOM IT MAY CONCERN:

Be it known that I, CHARLES A. SMITH, of New York, in the county of New York, and State of New York, have invented certain new and useful Improvements in Lifting-Jacks; and I do hereby declare that the following is a full, clear, and exact description thereof, reference being had to the accompanying drawings, and to the letters of reference marked thereon, which form a part of this specification, and which represents a sectional elevation of the same.

The nature of my invention consists in the general arrangement of a lifting-jack, by the use of which bodies of any weight may be raised with perfect ease.

And in order to enable others skilled in the art to which my invention appertains to make and use the same, I will now proceed to describe its construction and operation.

A represents a box or casing of suitable material, and of any dimensions required, one side of which is grooved.

In this groove a slide, B, moves up and down, and a slot in the upper end of said casing allows it to extend above the same when raised.

To the inner side of this slide B is firmly secured a ratch-bar, C, or the slide and ratch-bar may be made or cast solid in one piece if so desired.

Near the upper part of the casing A, a shaft, a, passes through the same, which shaft has its bearings in the front and rear sides of said casing.

On the shaft a, three wheels are firmly secured: one, a ratchet-wheel, D, which is placed near or against the rear side of the casing, and between said rear side and the slide B; one, a cog-wheel, E, which gears into the cogs of the ratch-bar C; and the third a safety-wheel, F, between the slide B and the front side of the casing, the use of which will be hereinafter set forth.

On each side of the ratchet-wheel D an arm, G, is placed on the shaft a, which arms extend through a slot in the side of the casing.

Between and to these arms a lever, H, is firmly secured. A pawl, I, is also pivoted between said arms, which pawl extends through the slot already mentioned in the side of the casing, above the ratchet-wheel D, and its inner end being provided with a hook, as shown, it catches the teeth of said wheel, so that by moving the lever H downwards, the ratchet-wheel D is turned, and as, at the same time, the cog-wheel E is revolving, the slide B will be raised above the casing A.

A spring, b, secured to the end of the lever H, presses the hooked pawl I in the teeth of the ratchet-wheel, and when the lever is raised again, said spring gives enough to allow the pawl to glide over the teeth, catching into another when the lever is again lowered.

In the rear side of the casing, another pawl, K, is pivoted, which is of the same construction as the pawl I, and which is also pressed in the teeth of the ratchet-wheel D, by a spring, d, thus preventing the said wheel from turning backwards when the downward pressure on the lever H is removed.

The additional wheel F is used when the weight is so heavy that the slide B would move down, although the pawl I catches the teeth of the ratchet-wheel. For this purpose a spring-band, i, is passed around said wheel and secured to a handle, L, in such a manner that, by pressing down on said handle, the wheel F is prevented from revolving, and, of course, thereby preventing the cog-wheel E from giving way, and holding the slide B up in the desired position.

Having thus fully described my invention, what I claim as new, and desire to secure by Letters Patent, is—

The combination of the lever H, ratchet-wheel D, cogged wheel E, slide B, ratch-bar C, with the safety-wheel F, and brake or safety-band i, all constructed as described, and operating substantially as and for the purposes herein set forth.

In testimony that I claim the foregoing as my own, I affix my signature in presence of two witnesses.

CHARLES A. SMITH.
